UNITED STATES PATENT OFFICE.

PINKNEY BRADFORD HOOD, OF SCIENCE HILL, KENTUCKY.

SIGNALING DEVICE FOR RAILROAD-CROSSING GATES.

Application filed September 17, 1925. Serial No. 56,850.

This invention relates to automatic signaling devices for railroad crossings which may be used in conjunction with the various types of safety devices now employed.

5 The main object of this invention is to construct a device which is unique both in construction and appearance, and which will plainly show the motorist whether it is safe or dangerous for him to make the crossing.

10 Another object is to construct the signal device in such a manner that the operation thereof will be controlled by the train.

15 Other objects will be apparent from the accompanying drawing and specification.

In the drawing

Figure 1 is an elevation of the signal device showing the revolving drum in its normal position with the words reading 20 "Go" "Track clear";

Figure 2 is a vertical section of the signal device;

Figure 3 is a horizontal section of the signal device;

25 Figure 4 is a diagram of the electrical wiring for the signal.

In carrying out this invention, I provide a cast metal housing 3 of any desired shape and design such as a watchman, which is mounted at the right side of the highway 1, when facing in the direction of travel, on either side of the railroad crossing 2. The breast portion of the said housing 3 is partially cut out as shown at 4, and a drum 5 mounted therein upon a shaft 6. The said shaft 6 extends down into the body portion 7 of the said housing 3 wherein it is journaled in bearings 9 and 17. A coil spring 8 is mounted over the shaft 6 and has its upper end secured in the said shaft 6 while its lower end is secured in the bearing support 17. A solenoid 10 is mounted in the body portion 7 and adapted to operate a plunger head 11 which is mounted in the said housing 3 and connected to the shaft 6 by means of a cable 12. The drum 5 is provided with a notched portion 18 along its lower edge for a purpose to be later explained. The said drum 5 is also pierced with the words "Go track clear" on the side which is normally exposed, and with the words "Stop train coming" on the opposite side or side which will only be exposed at intervals. A bracket 13 carrying a red light 14 is mounted upon the shaft 6 in back of the words "Stop train coming" of

the drum 5. A switch comprising two distinct sets of conductor terminals, the fixed half 15 of which depends from the upper bearing support and the movable half 16 of which is mounted upon the drum 5, is provided and arranged in such a manner as to close thru frictional engagement of the said terminals when the said drum is rotated to show the words "Stop train coming". A spring set latch 19 is pivoted in the housing 3 through its medial portion and with its tooth end is passed through the wall of the said housing 3, while its shank engages the notch 18 of the drum 5. Rigidly secured 70 arms 20 and 21 are provided, and formed so that the arm 21 will hold a gong in front of the housing 3, while the arm 20 is divided at the elbow as shown at 22. The fore arm 23 which carries a hammer 24, is rigidly 75 secured to a shaft 25 which is journaled through the arm 20 and the wall of the housing 3. A lever 26 is secured to the inner end of the shaft 25 and operated by an electro-magnet 27 which is mounted directly below the end of the lever 26. A battery 28 and suitable wiring 29 are provided as shown in Figure 4.

The operation of the signal device is as follows: During the greater part of the 85 time, there is no connection between the rails of the insulated section of the railroad tracks, and during which time the drum reads "Go track clear". As soon as a train reaches the insulated section of the 90 track and forms a connection between the said tracks, the solenoid 10 becomes energized and draws the plunger 11 toward itself, thereby partially rotating the shaft 6, so that the drum reads "Stop train coming" and the switch 15-16 is closed, thus lighting the red light 14 so as to illuminate the warning cut in the surface of the drum 5 and the immediate surroundings 95 through the words cut in the said surface of the drum. The partial rotation of the shaft 6 creates a tension upon the coil spring 8 so that when the contact formed by the train between the insulated tracks is broken, the said spring 8 will return the shaft 6 into its normal position. The circuit formed 100 through the train also energizes the electro-magnet which operates the hammer 24 through the medium of the shaft 25 and lever 26.

110 While I have herein described a certain specific manner and method of constructing

and assembling the elements of my invention, it is understood that I may vary from the same in minor details, not departing from the spirit of my invention, so as best 5 to construct a practical device for the purpose intended, as defined in the appended claims.

I claim:

1. In combination with a railroad crossing, a signal device as described, embodying 10 a housing; a drum for partial rotation mounted in the housing; the surface of the said drum being pierced with the words "Go track clear" and "Stop train coming"; means 15 controlled by the train for the rotation of the drum; a gong mounted in front of the housing; a lever and operating means controlled by the train for operating the gong.

2. In combination with a railroad crossing, 20 a signal device as described, embodying

a housing; a spring set shaft journaled in said housing; a drum, the surface thereof being pierced with the words "Go track clear" and "Stop train coming" secured to the said shaft; a plunger slidingly mounted 25 in the said housing; a cable secured to said shaft and said plunger; a solenoid mounted in said housing for operating said plunger; a gong mounted in front of said housing; a hammer pivotally secured to said housing 30 for ringing said gong; a lever secured to said hammer, extended into said housing; an electro-magnet mounted in said housing for operating said lever; and electric means connected with insulated tracks for the simultaneous operation of the solenoid and electro-magnet, when a train forms a circuit. 35

In testimony whereof I affix my signature.
PINKNEY BRADFORD HOOD.
